UNITED STATES PATENT OFFICE.

BENJAMIN GUSSETTIE, OF WARD SPRINGS, MINNESOTA.

WAGON-BRAKE.

1,073,752.

Specification of Letters Patent. Patented Sept. 23, 1913.

Application filed February 19, 1913. Serial No. 749,523.

To all whom it may concern:

Be it known that I, BENJAMIN GUSSETTIE, citizen of the United States, residing at Ward Springs, in the county of Todd and 5 State of Minnesota, have invented certain new and useful Improvements in Wagon-Brakes, of which the following is a specification.

The present invention relates to certain 10 new and useful improvements in wagon brakes, and has for its object to provide a device of this character which embodies novel features of construction whereby the brake is automatically applied when the 15 draft animals pull rearwardly upon the neck yoke, thereby eliminating the necessity for manually applying the brake.

A further object of the invention is to provide an automatic brake of this character 20 which is peculiarly constructed so that the brake is rendered inoperative when the vehicle is backed.

With these and other objects in view, the invention consists in certain novel combinations and arrangements of the parts as will 25 more fully appear as the description proceeds, the novel features thereof being pointed out in the appended claims.

For a full understanding of the invention, 30 reference is to be had to the following description and accompanying drawings, in which:—

Figure 1 is a longitudinal sectional view 35 of a vehicle provided with an automatic brake constructed in accordance with the invention, portions being broken away and removed. Fig. 2 is a top plan view of the rear portion of the running gear, showing the manner of mounting the brake beam and 40 brake levers thereon. Fig. 3 is an enlarged sectional view on the line 3—3 of Fig. 2, the brake shoe being indicated by dotted lines in the position assumed when the vehicle is backed. Fig. 4 is a detail sectional view 45 on the line 4—4 of Fig. 3. Fig. 5 is a detail view of the clamping block which is applied to the looped rear end of the cable. Fig. 6 is a vertical longitudinal sectional view through the tip at the forward end of the 50 wagon tongue. Fig. 7 is a plan view of the tip at the forward end of the wagon tongue. Fig. 8 is an enlarged transverse sectional view on the line 8—8 of Fig. 6, and Fig. 9 is a detail view of the neck yoke.

55 Corresponding and like parts are referred to in the following description and indi-

cated in all the views of the drawings by the same reference characters.

Referring to the drawings, the character A designates the running gear of a wagon, 60 B the wagon body, and C the tongue, the said parts being all of the usual or conventional construction and the running gear A including a reach 1. A transversely disposed brake beam 2 is rigidly mounted upon the reach 1 at a point slightly in advance of the rear wheels 3. A brake lever 4 is pivotally mounted at a point between its ends, as indicated at 5, upon each end of the brake beam 2. The inner arm of each of the brake levers 4 is loosely received within a keeper 6 upon the brake beam 2, while the outer arm of each of the levers operates within a keeper 7 upon the brake beam 2.

The outer end of each of the brake levers 75 4 carries a brake shoe 8 which is adapted to be brought into engagement with the rear wheel 3 so as to check the forward movement of the vehicle in the usual manner. The brake shoe 8 is shown as dove-tailed at 80 9 into a brake block 10, the rear face of the brake block having a bearing plate 11 applied thereto. This bearing plate 11 serves to loosely engage the cross bar of a U shaped link 12 by means of which the brake block 85 is loosely mounted upon the brake lever 4. The extremities of the U shaped link 12 are extended outwardly at 12' and pivotally mounted within bearings 13 which are applied to the brake lever. A flexible spring 90 strip 14 serves to engage the brake block 10 to hold the same yieldingly in an operative position, one end of the spring strip being secured at 15 to the brake lever 4, while the opposite end thereof is inserted in the dove-tail joint 9 between the brake block 10 and the brake shoe 8. Fastening members 16 which pass through the brake block 10 serve to secure the bearing plate 11 and the brake shoe 8 to the brake block, one of the said 100 fastening members also engaging the end of the spring 14. By pulling the inner end of the brake lever 4 forward the rear end of the said brake lever is moved rearwardly so as to bring the brake shoe 8 into engagement 105 with the rear wheel 3. When the vehicle is moving in a forward direction, the brake shoe 8 will be swung downwardly until the pivot link 12 engages the brake lever 4 and has the swinging movement thereof checked. 110 The brake shoe will then act upon the wheel to impede and check the movement of the

the action of the yielding means to throw the brake shoe into operative position.

2. A wagon brake including a brake beam adapted to be applied to the wagon reach, 5 brake levers pivotally mounted between their ends upon opposite ends of the brake beam, brake shoes carried by the outer ends of the brake levers, a slide mounted upon the brake beam under the inner ends of the brake 10 levers, projections upon the slide loosely engaging opposite sides of the inner ends of the brake levers, a guide rod projecting from the brake beam and loosely engaging the slide, a spring surrounding the guide rod 15 and engaging the slide for moving the same in one direction to move the friction shoes into an inoperative position, and means for moving the slide against the action of the spring to throw the brake shoes into 20 operative position.

3. A wagon brake including a brake beam adapted to be applied to the wagon reach, 25 brake levers pivotally mounted between their ends upon opposite ends of the brake beam, brake shoes carried by the outer ends of the

brake levers, keepers upon the brake beam for receiving the ends of the brake levers and limiting the movement thereon, a slide mounted upon the brake beam under the inner ends of the brake levers, one end of the 30 slide being deflected laterally and provided with a guide opening, projections upon the slide engaging opposite sides of the inner ends of the brake levers, a guide rod projecting from the brake beam and passing 35 loosely through the guide opening of the slide, a spring surrounding the guide rod and engaging the slide for moving the same in one direction to swing the brake levers and bring the brake shoes into an inoperative 40 position, and means for moving the slide against the action of the spring to throw the brake shoes into an operative position.

In testimony whereof I affix my signature in presence of two witnesses.

BENJAMIN GUSSETTIE.
